UNITED STATES PATENT OFFICE.

OLE P. NOISSOM AND OLE P. LUNDE, OF SOUTH BEND, INDIANA.

ELECTRIC TIME-SWITCH.

1,045,735.

Specification of Letters Patent.

Patented Nov. 26, 1912.

Application filed June 13, 1911. Serial No. 632,867.

To all whom it may concern.

Be it known that we, OLE P. NOISSOM and OLE P. LUNDE, citizens of the United States, residing at South Bend, in the county of St. Joseph and State of Indiana, have invented new and useful Improvements in Electric Time-Switches, of which the following is a specification.

The object of the invention is to provide means for automatically and abruptly opening and closing an electric switch at predetermined times.

To this end, the invention consists in the combination of a clock mechanism and switch throwing mechanism, the broad features of which are shown in Letters Patent granted to Noissom and Lindewald, and numbered respectively 907,088 and 934,340.

Specific details of construction and objects therefor will be better understood from the following description, taken in connection with the accompanying drawings, in which:

Figure 1 is a face view, with the door of the casing removed. Fig. 2 is a detail elevation of the upper end portion, with the dial and hands removed. Fig. 3 is a detail side elevation of the clock mechanism. Fig. 4 is a plan view of the same. Fig. 5 is a detail section of the upper portion of the clock mechanism on the line 5—5 of Fig. 4, looking in the direction of the arrow. Fig. 6 is a similar view on the line 6—6 of Fig. 4, in the direction of the arrow. Fig. 7 is a detail perspective view, partly in section, of one of the setting disks and its support and arbor. Fig. 8 is a transverse sectional view of the same. Fig. 9 is an elevation of the power spring and its casing. Fig. 10 is a detail perspective of the driver. Fig. 11 is a detail, showing in full lines the normal position of the switch operating lever and driver with the switch closed, and in dotted lines the position of the parts prior to the driver elevating the operating lever.

5 designates the casing, 6 the dial, 7 the hands which are secured to the arbor 8. The setting disks 9 and 10 are numbered to correspond approximately to the number of hours of light and darkness in the day, the dark portion of the surface corresponding to night and the light portion to day, and each of these surfaces having numerals reading in regular order from 6 to 12, inclusive, and 55 from 6 to 1 inclusive. The toothed wheels 12 and 13 have outwardly extending studs

14, the outer ends of which receive the peripheries of the setting disks 9 and 10. The arbors 16 and 17 which support the wheels 12 and 13 are split, so as to frictionally engage the studs 18 secured to the frame 19. The toothed wheels 12 and 13 are actuated to move in the same direction by the minute pinion 20, the latter being connected in the well-known manner with the other parts of the movement. A double-ended controlling lever 21 is arranged on the frame 19, the end portions 22 and 23 thereof extending into the space between the frame and toothed wheels 12 and 13, and into the path of movement of cam studs 24 carried by disks 25 fixed to the arbors 16 and 17. With this construction, it will be seen that when a key or other suitable instrument is inserted into either of the sockets 27 at the outer ends of the arbors, the disk 25 and the indicator hand 29 will be turned simultaneously, this turning movement moving the stud 24 nearer or away from the adjacent end of the lever 21, as the case may be. It will be observed, 80 however, that when the toothed wheels 12 and 13 are turned by the minute pinion 20, the setting disks 9 and 10 and the disks 25 being rigidly mounted on the same arbor will also turn, so that at the proper time, one of the studs will engage the lever 21 and operate the same, for a purpose to be presently described.

A rock shaft 30 carried by the frame 5 has a crank 31 which bears against a cam 90 surface 32 on the lever 21, and the lever is held in the position shown by means of a leaf spring 35, so that when one end of the lever is engaged by one of the cam studs, as before described, the cam surface 32 of the 95 lever will operate to turn the crank 31 until the cam stud moves from engagement with the end of the lever, whereupon the parts will be restored to their normal positions, as shown.

The rock shaft 30 has a pawl 34 which is normally arranged in the cam slot 35 of a disk 36 carried by an arbor 37. A toothed wheel 38 on the arbor 37 is connected with the toothed wheel 39 carried by an arbor 40. An arbor 41 arranged adjacent to the rock shaft 30 has a dog 42 which engages with studs 43 on the wheel 39, and a locking dog 44 carried by the arbor 30 has an end portion adapted to successively enter 110 notches 45 in a disk 46 secured to the arbor 47 of the power spring 48, the power spring

being connected, through a train of gearing 49. The rock shaft 30 has a tripper 50 which underlies the locking dog 44, so that when the rock shaft is moved, as before described, the engaging end of the locking pawl will be moved from engagement with the disk 46, and so also will the dog 42 be moved from engagement with the stud 43, and further the pawl 34 will be moved from 10 the cam slot 35, whereupon the spring motor will be released and rotate until the engaging end of the locking pawl moves into the next succeeding notch.

The casing 51 of the power spring is provided with outwardly extending studs 52 arranged in spaced relation, as shown. The studs 52 are adapted to consecutively engage the angular bent end portion 53 of a driver 54. The driver 54 is pivoted to a 20 block 55 in the casing 5, and a retractile spring 56 connects the outer end of the driver to the upper end of the casing.

A switch stand 57 is arranged at an angle with respect to the casing, and is secured 25 to a bracket 58 in the lower end of the casing. The wires 59 of the external lighting circuit connect to the switch stand, as shown, so also do the wires 60 of the internal circuit. An operating rod 61 is pivoted at 30 its lower end to the cross piece 62 of the switch blades 63. The upper end portion of the operating rod extends through a guide 64 on the driver 54, and is provided on its opposite sides with spaced projections 35 65 and 66.

In the normal position of the parts and with the switch open, the lower projection 65 is above the guide 64 of the driver, assuming now that the mechanism has been 40 set to turn on the lights at the hour indicated on the setting disk to the left in Fig. 1. When the hands 7 move to the hour indicated on the said setting disk, the stud on the disk 25 on the left in Fig. 1 will 45 trip the lever 21, whereupon the power spring and its casing will move, as before described. This movement of the casing 51 will effect engagement between one of the studs 52 thereof and the angular bent portion 53 of the driver, whereupon the said angular bent portion 53 will be elevated to 50 the position shown by dotted lines in Fig. 2. When the driver is in this position, it will be seen that the spring 56 is tensioned, 55 and when the inner end of the guide clears the lower projection, the rod 61 will be moved slightly inwardly by means of a leaf spring 67 secured to the cross piece 62, so that the inner end of the guide will be 60 directly over the upper surface of the extension 65, and when the stud 52 on the casing 51 moves from engagement with the angular bent portion 53, the said end portion will move downwardly under action of the 65 spring 56, thus causing the inner end of the

guide to abruptly strike the extension 65 with considerable force, whereby the movable portion of the switch will be forced downwardly and into engagement with the contacts 68.

When the switch moves to closed position in the manner just described, the rod 61 will be thrown outwardly by means of a leaf spring 68 secured to the cross piece 62 and the upper end portion of the rod 70 directly above the projection 66 will bear upon the outer end of the guide 64. Assuming now that the setting disk on the right in Fig. 1 of the drawings has been set to the hour indicated thereon, it will 75 be seen that when the hands 7 move to the hour corresponding to that indicated on the disk, the power spring will be released and the driver moved, as before described. It will be seen that as the inner end of the 80 driver moves upwardly, the outer end thereof will move downwardly until it clears the projection 66, whereupon the rod 61 will be moved outwardly under the action of the spring 69 and into the position shown. 85 When the driver has been released in the manner before described, the outer end thereof will move upwardly in an abrupt manner under the action of the spring and strike the extension 66 with considerable 90 force, whereupon the movable member of the switch will be raised to the position shown and the parts set to be operated, as 95 before described.

The switch is held in raised position by 100 means of a spring latch 17 secured at one end to the casing 5, and has its opposite end adapted to yieldingly engage the cross piece 62, when the switch is thrown upwardly. The engagement between the latch and cross 105 piece is such as to overcome the combined weights of the movable part of the switch and operating rod 61.

It might here be stated that the drawings and description illustrate and describe one 110 embodiment of our invention, and it is to be understood that we are not to be limited to the said showing and description, since it will be manifest that various changes may be made, within the scope of the appended 115 claims, without departing from the spirit, or sacrificing any of the advantages of the invention.

What is claimed is:

1. In an electric time switch, in combination with a movable switch member; of a switch opening and closing mechanism including a movable driver, and an element connected to the switch member and shiftable thereby into position to engage with different portions of the driver.
2. In an electric time switch, in combination with a movable switch member; of a switch opening and closing mechanism including a movable driver, an element con-

nected to the switch member and shiftable thereby into position to engage with different portions of the driver, and means for yieldingly holding said element in its shifted 5 positions.

3. In an electric time switch, in combination with a movable switch member; of a switch opening and closing mechanism including a horizontally disposed movable 10 driver, and means connected with the switch member and adapted to be abruptly driven in different directions alternately by the opposite ends of the driver.

4. In an electric time switch, in combination with a movable switch member, of an operating rod connected thereto, of a switch opening and closing mechanism including a horizontally disposed movable drive member, of a guide member mounted on the said 20 drive member and adapted to slidably receive the upper portion of the operating rod and to move the same in opposite directions.

5. In an electric time switch in combination with a movable switch member, of a switch opening and closing mechanism including a horizontally disposed movable driver, a spring motor, and means actuated by the motor to move the free end of the 30 said driver in an upward direction, an operating rod connecting the said switch member, and means carried by the opposite end of the said driver and operating to

abruptly drive the said operating rod in opposite directions.

6. In an electric time switch, in combination with a movable switch member, of a switch opening and closing mechanism including a horizontally disposed movable driver, and a combined guide and actuating 40 member carried by the said driver, an operating rod connecting the said switch member and having its upper portion movably mounted in said combined guide, and actuating surfaces formed on the rod and 45 adapted to engage the said actuating member of the driver.

7. In an electric time switch, in combination with a movable switch member, of a switch opening and closing mechanism including a horizontally disposed driver, and a combined guide and actuating member mounted on the said driver, an operating rod connecting the said switch member, the said rod having its upper portion formed to provide spaced superimposed actuating surfaces 50 adapted to alternately engage the said actuating member of the driver at different points thereon.

In testimony whereof we affix our signatures in presence of two witnesses.

OLE P. NOISOM.
OLE P. LUNDE.
